UNITED STATES PATENT OFFICE.

GEORGE F. ROYER, OF WILKES-BARRE, PENNSYLVANIA, ASSIGNOR TO ROYER FOUNDRY & MACHINE CO., OF WILKES-BARRE, PENNSYLVANIA, A CORPORATION OF PENNSYLVANIA.

SAND SEPARATING AND BLENDING MEANS.

Application filed October 30, 1925. Serial No. 65,792.

The present invention relates to improvements in apparatus or machines including the subject matter of a prior Patent No. 1,559,915, and has for its particular object to 5 provide an automatically acting means for lifting the material to be treated from the floor or surface on which the machine rests and discharging the same onto the separating belt.

As clearly set forth in the aforesaid patent, the machine includes as an essential element an endless belt mounted in an inclined position, and provided with outwardly projecting, closely adjacent, metal sprigs. In 15 use this belt is driven at a relatively high speed by a suitable motor, and the granular material to be treated is deposited on the upper run thereof. The action of the belt on the mass of material deposited thereon 20 effects a separation of minute particles from such mass which are collected in the interstices between the metal sprigs, and as the belt travels over its upper supporting roll these collected particles are discharged in a 25 stream, being projected from such roll for a considerable distance, thus aerating and thoroughly blending the separated particles.

As previously stated, the particular object of the present improvements is to provide 30 a means by which the material to be treated may be lifted from the floor or surface on which the machine rests and delivered to the material treating belt. The machine is particularly designed for use in the 35 preparation of sand or material used in the formation of moulds employed for shaping fluid metal and as the piles of such material may be located at widely separated points on the foundry floor, or it may be desired to 40 effect a discharge of the separated and blended material at points relatively distant from such supply piles, the machine preferably includes a wheeled supporting frame and means for propelling it from place to place, 45 such movement being guided by suitable steering devices.

By the present invention there is provided a machine of the type or character of my aforesaid earlier patent, which may be readily moved from place to place over a foundry floor, and by which the material to be treated 50 can be lifted from the floor and delivered onto the treating belt with a minimum amount of attention from an operative. 55 Movement of the machine from place to

place, as well as control of the automatically acting loading devices, may all be controlled by a single attendant so that the expense of operating the mechanism is reduced to a minimum.

In the accompanying drawings some of the parts are shown more or less conventionally, and particularly the material treating belt, and its control means, are not shown in the same detail as in the earlier 60 patent which is more particularly directed to these elements.

There can, of course, be considerable modification and possible rearrangement of the several parts of the mechanism without departing from the invention, and it is to be understood that except where specifically described in the appended claims, the invention is not to be considered as limited to the exact details illustrated. In other words, 70 the drawings are intended to be illustrative 75 rather than restrictive of the invention.

In the drawings:—

Figure 1 is a side elevation of a machine embodying the present invention.

Figure 2 is a plan.

Figure 3 is an elevational detail of the lifting devices.

Figure 4 is a detail of portions of the gearing provided for propelling the machine 85 from place to place.

Figure 5 is a detail illustrating the manner in which the material lifting means is operated to effect delivery of the material carried thereby to the treating belt.

Figure 6 is a sectional detail, substantially 90 on the line 6—6 of Figure 2.

Referring to the drawings, in the several figures of which like reference characters designate corresponding parts, the improved 95 machine includes a main supporting frame which is mounted upon suitable ground wheels 1, 2, located respectively adjacent its forward and rear ends.

The wheels 1 are loosely mounted on a 100 suitable axle 3, while the wheels 2 are preferably connected by a yoke 4, which has an upwardly extending spindle-like member engaging a suitable bearing on the frame, so that said wheels may be turned about a 105 vertical axis for guiding the movement of the machine from place to place.

For effecting such movement of the steering wheels the yoke 4 is shown as connected to a toothed segment 5, with which meshes 110

a pinion 6 at the lower end of a shaft 7. The shaft 7 is supported in suitable bearings on the main frame, and at its upper end has secured thereto a bevel gear 8, which meshes with a coacting gear on a substantially horizontal shaft 9 provided at its other end with a hand wheel 10. By turning the hand wheel 10 the steering wheels 2 may be readily adjusted about a vertical axis to control the direction of travel of the machine as desired.

In suitable uprights on the wheel supporting frame are journalled the rollers about which the material treating belt 11 passes. This belt is of the character described in detail in the earlier Patent 1,559,915, and, as in the machine of that patent, is arranged in an inclined position, its rear, discharge end, being at the highest point and so positioned that the separated particles collected by the belt will be discharged rearwardly from the machine and to a considerable distance.

Power for driving the separating belt 11, at the necessary high speed is provided by a motor arranged within a suitable casing 12, which is, in the embodiment of the invention illustrated, located below the separating belt, being directly mounted on the body of the wheel supporting frame. Preferably, an electric motor is employed and the current therefor is supplied through a suitable conductor 13, which is of sufficient length to permit the machine being moved over a considerable area.

A suitable hopper comprising side walls 14 and end walls 15 is provided above the material treating belt.

20 designates the body of the receptacle or shovel by which the material to be treated is lifted from the floor or surface on which the machine rests and conveyed to a position to be discharged into the aforesaid hopper and onto the upper surface of the material treating belt 11. As shown, this shovel or receptacle is of scoop-like form, provided at its opposite sides with rearwardly extending arms 21, which are pivotally connected to the wheeled supporting frame so that the shovel may be bodily swung from the position shown in full lines in Figure 1, to that represented in dotted lines. In the embodiment of the invention illustrated, the shovel supporting arms 21 are mounted to turn about the axis of the front axle 3 of the wheeled supporting frame, and are of such length that the shovel is supported in advance of the frame and, when in its lowered position, will be caused to enter a pile of sand in the path of the machine as the latter moves over the foundry floor. By thus moving the machine the shovel may be automatically loaded and then, by the means hereinafter described, the arms 21 can be swung upward about their pivotal connec-

tion and the collected material brought into a position above the material treating belt 11.

For effecting the necessary vertical, swinging, movements of the shovel, the embodiment of the invention illustrated includes two cables 22, each being connected at one end, as 23, to the side walls of the shovel 20, preferably adjacent the forward end thereof. At their rear ends the cables 22 are connected to winding drums 24, which are loosely mounted on a shaft 25 journalled in suitable bearings on the wheel supporting frame and adapted to be rotated by gearing, hereinafter described, from the motor in the casing 12.

As shown, the shaft 25 is provided at one end with a sprocket 26, which, through a chain 27, is connected to a smaller sprocket 28 on a power shaft 29. A second sprocket 30 on the shaft 29 is, through a chain 31, connected with a sprocket at one end of the shaft 32, which constitutes the support for the upper end of the material treating belt 11.

Friction clutches 35 are provided for connecting the winding drums 24 to the shaft 25, movement of such clutches being effected through bell crank levers 36, each having one arm connected by suitable links to a control lever 37. Referring to Figure 3, it will be seen that as the lever 37 is rocked, the two clutches 35 will be simultaneously actuated to engage the winding drums with the shaft 25 or release such connection as desired.

By properly manipulating the lever 37, it will be possible, therefore, to raise the conveying shovel from the full line position shown in Figure 1 to that represented by dotted lines, and when said lever is actuated to disengage the clutches 35, the shovel will, automatically, by gravity, return to its lower position.

Such return movement of the shovel is controlled by friction brake bands 40, which by manipulation of a suitable lever 41 are caused to exert a retarding effect upon the unwinding movement of the drums 24. This brake mechanism may also be employed to retain the shovel at any desired elevated position when the clutches 35 are disengaged. This enables the shovel 20 to be loaded at one point, and after it has been elevated to the desired extent, but prior to reaching its discharging position, the machine may be bodily moved to another place in the foundry and thereafter the upward movement of the shovel continued (by properly manipulating the brake lever 41 and clutch controlling lever 37) to bring it into the discharging position and automatically effect delivery of its contents onto the material treating belt, as hereinafter referred to.

The portion 20^a of the rear end wall of the

shovel 20 is supported to be movable relative to the side walls and bottom of the shovel. As shown, this rear end wall is supported by a bail 50, the ends of which are connected 5 to arms 51 pivotally engaged with the side walls of the shovel, as at 52, and each provided at its rear end with a roller 53.

As the shovel is lifted, by actuation of the winding drums, the rollers 53 contact 10 with, and ride along, the upper edges of guides 55, or outwardly extending flanges on the side walls of the hopper that project over said guides, and, as the upwardly swinging movement of the shovel supporting arms 21 continues the contact of the rollers 53 with said guides 55 and flanges on the hopper acts to move the rear end wall section 20^a from contact with the relatively stationary part of such end wall, as illustrated in Fig. 5, thus providing an outlet 15 for the discharge of the contents of the shovel onto the material treating belt.

For propelling the machine, each of the forward ground wheels 1 is provided with a 20 sprocket 60 that is connected by a chain 61 with a sprocket 62 at one end of a shaft 63. The shaft 63 extends parallel and adjacent the power shaft 29, both said shafts passing through a suitable casing 64 within which is 25 arranged the gearing that will now be described by which power is communicated to the shaft 63 and the direction of rotation thereof controlled.

On the shaft 29 within the casing 64 are 30 secured a gear 65 and sprocket 65^a. The gear 65 meshes with a gear 66 carried by a sleeve loosely mounted on the shaft 63 and also provided with one member of a friction clutch, by which said sleeve and gear, 35 66, may be secured to the shaft 63 to effect rotation thereof in one direction. The sprocket 65^a on the shaft 29 is, through a suitable chain, connected with a sprocket 67 carried by a sleeve loosely mounted on the shaft 63, 40 said sleeve being also provided with one member of a friction clutch, whereby it may be secured to, or released from, the shaft 63. It will be seen that when the gear 66 is 45 clutched to the shaft, power from the shaft 29 will drive the shaft 63 in one direction and through the chains 61 and sprockets 60 effect movement of the wheel supporting frame in one direction, whereas by disconnecting the gear 66 from the shaft 63 and 50 clutching the sprocket 67 to such shaft the direction of rotation of the shaft and consequent movement of the wheel supporting frame will be reversed. For effecting actuation of the two friction clutches 70, 71, 55 use is made of a shifting rod 72 having at its outer end a suitable handle and connected within the casing 65 to a clutch operating lever 73. The lever 73 is connected to the two friction clutch members 70, 71, so that 60 as said lever is rocked in one direction the

gear 66 will be connected with the shaft 63, and when the clutch lever is shifted in the opposite direction the sprocket 67 will be connected while the gear 63 will be released. When the clutch shifting parts occupy the 70 intermediate position illustrated in the drawing, both of the friction clutches are disengaged and the machine will remain stationary.

It is believed that the manner of using 75 and the advantages of the improvements will be readily appreciated from the foregoing description in connection with the drawings.

It will be seen that the several manually operable devices (namely, the levers 37, 41, 80 and shifting rod 72) for controlling actuation of the means for lifting the shovel, retaining it against movement or controlling downward movement thereof and for controlling forward or backward movement of 85 the vehicle, as well as the hand wheel 10 for steering the machine, are all readily accessible by a single operative, and movements of the machine can be controlled in a very simple manner. 90

Assuming that the parts are in the relation shown in full lines in Figure 1, and the motor is operating to drive the material treating belt at the desired speed, the operator will shift the control rod 72 to effect 95 connection of the gear 66, for example, to the shaft 63, which will cause the machine to move forward and the shovel 20 to enter a pile of sand in the path of travel of the machine. When the shovel has been loaded 100 the control rod 72 will be shifted to release both clutches 70, 71, and the lever 37 shifted to connect the winding drums to the power shaft 25. As the cables 22 are wound upon the drums 24, the shovel will be swung upward to a position above the material treating belt 11. As this upward movement of the shovel continues, the rollers 53 riding on the guides 55 will effect an opening movement of the rear end wall section 20^a of the 105 shovel, permitting the contents of the latter to fall upon the material treating belt. The particles separated from the mass by such belt will be discharged in a stream from the rear upper end of the belt to a considerable 110 distance from the machine, as explained in the earlier application before referred to. In case it is desired to shift the machine bodily after the shovel has been loaded, and before depositing the contents thereof upon the belt, the operator will move the lever 37 to release the winding drums from their power shaft and actuate the brake control lever 41 to prevent movement of said drums. With the parts in this position, as indicated 115 in dotted lines in Figure 1, the machine with the loaded shovel elevated may be moved to any desired point, and, therefore, by releasing the brakes and properly moving the clutch lever 37 the winding drums will be 120 125 130

again connected to the power shaft and the slight additional upward movement of the shovel will effect an opening of the discharge aperture from the shovel.

5 I claim:—

1. A machine of the class specified, comprising a wheeled supporting frame, a motor on said frame, material treating means on the frame actuated by the motor, material feeding means operated by the motor for periodically lifting material from the surface on which the machine stands and delivering it to the material treating means, and manual control devices operative to 10 vary the periodic operations of said feeding means and to interrupt the movement thereof between the loading and discharge positions, whereby the position of the machine may be shifted after a charge of material 15 has been lifted from the surface on which the machine stands and prior to its being discharged from the shovel, so that a plurality of charges collected by the shovel at different points may be simultaneously 20 delivered to the material treating means.

2. A machine of the class specified, comprising a wheeled supporting frame, a motor on said frame, two arms pivotally connected to and projecting from the frame, 25 connections between the motor and said arms for swinging the arms upward about their pivots, a shovel supported between said arms to be positioned beyond the frame when the arms are lowered, the shovel being provided 30 with a relatively movable end wall, a hopper on the frame, inclined guideways at opposite sides of the hopper, rollers projecting laterally from the movable end wall of the shovel and adapted to ride on said guideways as the shovel supporting arms are 35 swung upward, whereby the end wall of the shovel will be adjusted to effect discharge of the contents of the shovel into the hopper at 40 a predetermined point in the upward travel 45 of the shovel, means on the frame actuated by the motor for treating material discharged into the hopper, and manually operable controlling devices for interrupting the upward movement of the shovel and 50 holding it stationary at an intermediate point in its travel.

3. A machine of the class specified, comprising a wheeled supporting frame, a motor on said frame, connections between the 55 motor and wheels of the supporting frame for propelling the machine, a shovel pivotally connected to the frame and projecting therefrom in position to enter a pile of material in the path of movement of the 60 wheeled frame, means actuated by the motor for swinging the shovel upward about its pivotal connection with the frame, material treating means on the frame actuated by the motor and adapted to receive material dis-

charged by the shovel, and means for retaining the shovel stationary relative to the frame at any desired point intermediate its loading and discharge position.

4. A machine of the class specified, comprising a wheeled supporting frame, a motor on said frame, a pivotally supported shovel adapted to project from the frame, a winding drum supported on the frame above the path of material discharged from the shovel, means for actuating the drum 70 from the motor, cable connections between the drum and shovel for rocking the latter about its pivotal connection with the frame, motor actuated material treating means adapted to receive material discharged by the 75 shovel, and brake means adapted to cooperate with the winding drum for maintaining the shovel stationary relative to the frame at any desired point intermediate its loading 80 and discharge positions.

5. A machine of the character described, comprising a wheeled supporting frame, a motor on said frame, material treating means on the frame actuated by the motor, material feeding means comprising a receptacle pivotally connected to the frame, whereby it may be positioned upon the surface on which the machine stands or where it will deliver its contents to said material 90 treating means, means operated by the motor 95 for rocking said receptacle upward about its pivotal support from one of said positions to the other, means for automatically delivering the contents of the receptacle to the said material treating means when it has been 100 elevated to a predetermined point, and manual control devices for interrupting the lifting movement of said feeding means at points intermediate the loading and discharge positions of the receptacle, for the 105 purposes stated.

6. A machine of the character described, comprising a wheeled supporting frame, a motor on said frame, material treating means on the frame actuated by the motor, 110 material feeding means comprising a scoop-like receptacle connected to the frame and adapted to be positioned upon the surface on which the machine stands, or where it will deliver its contents to said material treating means, motor operated means for lifting said receptacle from one said position to the other, manual control devices operative 115 to connect said lifting means to the motor and to interrupt movement of the receptacle 120 and hold it stationary at points intermediate said terminal positions, and means for connecting the motor with one of the wheels of the supporting frame for bodily moving the 125 entire machine.

In testimony whereof I have hereunto set my hand.

GEORGE F. ROYER.
